DIVER'S WEIGHT BELT

Louis R. Despres, 99 Townsend Ave., New Haven, Conn.,
and Barney L. Goldwater, 50 Vanderbilt Ave., New
York, N.Y.

Filed June 16, 1965, Ser. No. 85,768

Term of patent 14 years

(Cl. D71—1)

FIGURE 1 is a perspective view of a diver's weight belt showing our new design,

FIG. 2 is an exploded view of the buckle end thereof, and

FIG. 3 is a fragmentary view looking in elevation on one set of weights.

The dominant features of our design reside in the portions shown in full lines.

We claim:

The ornamental design for a diver's weight belt, substantially as shown and described.
